[57] CLAIM

The ornamental design for an elastic connector for holding down a tarp, as shown and described.

DESCRIPTION

FIG. 1 is a perspective view of an elastic connector for holding down a tarp showing our new design;

FIG. 2 is a left end elevational view thereof;

FIG. 3 is a right end elevational view thereof;

FIG. 4 is a top plan view thereof;

FIG. 5 is a front elevational view thereof;

FIG. 6 is a bottom plan view thereof;

FIG. 7 is a rear elevational view thereof;

FIG. 8 is a sectional view taken along line 8—8 of FIG. 5;

FIG. 9 is a sectional view taken along line 9—9 of FIG. 5;

FIG. 10 is a sectional view taken along line 10—10 of FIG. 5; and,

FIG. 11 is a sectional view taken along line 11—11 of FIG. 5, all of FIGS. 2—11 being of a slightly smaller scale than that of FIG. 1.
